UNITED STATES PATENT OFFICE.

GINES PEREZ GOMEZ, OF MIAMI, ARIZONA.

DRILL CARRIAGE.

1,403,315.

Specification of Letters Patent. Patented Jan. 10, 1922.

Application filed December 2, 1920. Serial No. 427,687.

To all whom it may concern:

Be it known that I, GINES P. GOMEZ, a subject of the King of Spain, residing at Miami, in the county of Gila and State of 5 Arizona, have invented certain new and useful Improvements in Drill Carriages; and I do declare the following to be a full, clear, and exact description of the invention, such as will enable others skilled in the art to 10 which it appertains to make and use the same.

This invention relates to an improved mounting for a compressed air drill of the type used in mining and other similar work 15 and one object of the invention is to provide a device for mounting the drill which will include a tripod having a track connected therewith, a carriage being mounted upon the track and including means for engaging 20 threads of the track and feeding the carriage along the track as the drill operates to form a hole in a rock.

Another object of the invention is to so construct the carriage that the means for 25 imparting movement to the carriage may include a worm and means for rotating the worm including a paddle wheel rotated by means of compressed air which may be drawn from a source of supply or may be 30 obtained from the exhaust of the compressed air drill.

Another object of the invention is to so construct the device that the paddle wheel may be selectively turned to move the carriage 35 along the track towards either end desired.

Another object of the invention is to so construct this device that the carriage may be operated by hand if so desired.

Another object of the invention is to so construct this carriage that the compressed air drill may be firmly but releasably connected therewith and thus put in place and removed when desired.

Another object of the invention is to so construct the tripod that the track may be releasably connected with a disk forming part of the tripod and the track and carriage placed at a desired angle upon the 50 disk and releasably secured in the adjusted position.

Another object of the invention is to provide improved supporting legs for the tripod, one of the legs being adjustably mounted and releasably held in a set posi-

tion and the remaining legs being rigid with the disk and extending in diverging relation from the same.

This invention is illustrated in the accompanying drawings, wherein:

Figure 1 is a view showing the improved drill support in side elevation.

Figure 2 is a fragmentary top plan view looking down upon the drill carriage.

Figure 3 is a longitudinal sectional view taken along the line 3—3 of Fig. 2.

Figure 4 is a vertical transverse sectional view taken along the line 4—4 of Fig. 3.

Figure 5 is a sectional view taken along the line 5—5 of Fig. 1.

Figure 6 is a sectional view taken along the line 6—6 of Fig. 3.

Figure 7 is a sectional view taken along the line 7—7 of Fig. 1.

Figure 8 is a sectional view taken along the line 8—8 of Fig. 7.

This improved device is provided with a base or tripod including a disk 1 which is positioned vertically and has sockets 2 cast integral therewith in order to support the 80 diverging forward legs 3 which legs are provided with lower sections 4 telescoping in the upper sections and releasably held in a set position by set screws 5. The rear leg 6 is also provided with a lower section 7 which telescopes in the upper section and is releasably held in a set position by the set screw 8. The rear leg is carried by a casting 9 which is U-shaped and provided with arms 10 which extend upon opposite sides of the 90 disk and carry a pivot pin or bolt 11 by means of which the disk is rotatably mounted. A clamp or stay-bolt 12 has its curved or hooked end portion positioned in a slot 13 formed in one of the legs 10 and fitting 95 into a selected notch 14 formed in the disk 1 so that when the securing nut 15, which is carried by the threaded end portion of this bolt as shown in Figs. 7 and 8, is turned to tighten the clamp, the disk will be firmly 100 gripped and the adjustable legs securely held in a set position. It will thus be seen that by proper adjustment of the rear leg 6 the height of the tripod can be controlled.

The track 16 has its upper face cut to provide the threads 17. This track is positioned above the disk and is provided at its lower edge with a bead 18 for engagement by the spaced clamping jaws or blocks 19. These clamping jaws or blocks 19 are cut to engage 110

and conform to the curvature of the disk 1 and bolts 20 are passed through these blocks so that the blocks can be drawn together into tight binding engagement with the bead 18 5 and disk 1 and thus firmly hold the track in engagement with the disk with the track extending horizontal or at a desired incline. One end of said track is provided with a socket 21 so that if it is desired to increase 10 the length of the track, a second track section having an extended forward end portion may be put in place with the extended forward end portion fitting into the socket 21. The second track section would have a 15 construction similar to the main track section shown in Fig. 1 except that the forward end portion would be extended for fitting into the socket instead of having the forward end portion cut away as shown at 22 to provide a seat for the spring clip 23. This clip 20 23 is secured by a bolt 24 and extends upwardly to engage the drill steel 25 and guide movement of this drill steel when the drill is in operation.

25 The carriage is provided with an upper plate 26 which rests upon the threaded head of the track and is provided with depending side ribs 27 which extend upon opposite sides of the track as shown clearly in Fig. 5. Securing strips 28 are riveted or otherwise firmly connected with these depending side flanges and extend beneath the side portions of the track head as shown in this figure, so that the carriage may move longitudinally 30 of the track but may not become disconnected from the same. The lower strips 28 extend beyond the rear end of the upper plate and are provided with upwardly extending lugs 29 thus providing a seat between the lugs 29 and the rear end of the plate 26 to receive the base 30 of a housing 31. The housing 31 is secured to the extended rear end portions of the strips 28 by bolts or similar removable fasteners 32 and it will 35 thus be seen that when desired this housing may be removed for the purpose of cleaning the housing and mechanism contained therein and for making necessary repairs.

40 The housing 31 is formed in two sections 50 33 and 34 which are releasably connected by bolts 35 so that the housing may be taken apart to permit of access to the interior thereof. From an inspection of Fig. 3, it will be seen that the housing which is hollow 55 is formed to provide a chamber 36 in which a worm 37 is rotatably mounted and engages the teeth of the rack 17. This worm is provided with shaft extensions 38 and 39 mounted in bearings as shown in this figure, 60 the shaft extension 39 carrying a gear 40 which meshes with a smaller gear 41 positioned in the chamber 42 formed in the enlargement 43 of the housing. This gear 41 is carried by a shaft 44 which extends 65 through the fan chamber 45 of the housing

and carries a fan or paddle wheel 46. This paddle wheel is shown clearly in Figs. 3 and 4 and referring now specifically to Fig. 4, it will be seen that the fan chamber is elongated and tapered to an inlet in which a 70 sleeve valve 47 is rotatably mounted. This sleeve valve is provided with a handle 48 by means of which it may be turned as desired and is provided with a socket 49 at its outer end which is held in place by the turning 75 handle 48 and serves as a securing element to prevent longitudinal movement of the sleeve valve. This socket 49 receives one end portion of a hose 50 by means of which compressed air will be fed to the fan housing. 80 The sleeve valve is provided with an outlet passage 51 and from an inspection of Fig. 4, it will be readily seen that when the device is in operation, the sleeve valve may be turned to direct the air current over or under 85 the shaft 44 thus causing the fan or rotor 46 to rotate in a desired direction during passage of the air through the fan housing and out through the outlet openings 52.

90 When this support is in use, the compressed air drill 53 will be put in place as shown in Fig. 1 and secured by the clamps 54 carried by the upstanding ears 55 carried by the upper plate of the carriage. The usual air pipes for supplying air to the compressed air drill will be connected with this drill and the pipe 50 may be connected with the exhaust of the compressed air drill or with a suitable source of compressed air such as a compressed tank. The drill steel extends through the guide 23 and the steel will be held in the proper position and prevented from having excessive side movement when the drill is in operation. As soon as the air is turned on, the air passing through 100 the pipe 50 into the fan housing will engage the blades of the fan or rotor 46 and this will rotate the shaft 44 thus rotating the worm 37 through the medium of the gears 40 and 41. As the worm 37 rotates, the carriage will be moved longitudinally of the track and thus the steel advanced as it cuts its way through the rock. By proper adjustment of the sleeve valve, the rotor can 110 be operated to advance the carriage to feed the drill steel into the opening or hole formed in the rock and the valve can then be turned to reverse the rotation of the rotor and return the carriage to the rear end portion of the track. If it is desired to 115 operate the return by hand, the crank 55 will be put in place and releasably secured by the spring 56. When desired the various elements forming this drill support can be taken apart, repaired or cleaned and the device reassembled.

120 I claim:

1. A drill mount comprising a support including a track having threads cut in its upper face, a drill carrying carriage slidably 130

mounted upon said track, a housing carried by said carriage, a worm journaled in said housing and engaging the threads of said track, a driving shaft rotatably mounted 5 in said housing, means for transmitting rotary movement from said driving shaft to said worm, and a paddle wheel carried by the driving shaft, the housing having an air outlet and an air inlet having a control 10 valve eccentrically positioned therein for directing air against the paddle wheel rotating the paddle wheel in a predetermined direction.

2. A drill mount comprising a support including a track having threads cut therein, a drill carrying carriage slidably mounted upon said track, a housing carried by said carriage and having chambers formed therein, a worm rotatably mounted in one chamber and engaging the threads of said track, 15 a driving shaft rotatably mounted in the housing and having one end portion extending into the second chamber and its second end portion extending into the first chamber, 20 means for transmitting rotary movement from said shaft to said worm, and an air actuated rotor carried by said shaft in the second chamber whereby said driving shaft may be rotated through the medium 25 of compressed air from a drill carried by said carriage.

3. A support for a compressed air drill comprising a base including a threaded track, a carriage slidably mounted upon said track, a 35 housing carried by said carriage and having separable side sections releasably connected, said housing having a rotor chamber and a worm chamber formed therein, a worm rotatably mounted in the worm chamber 40 and engaging the threads of said track, a driving shaft rotatably mounted in the housing, and extending through the rotor chamber, a rotor mounted upon the driving shaft within the rotor chamber, co-operating gears 45 carried by the drive shaft and worm for transmitting rotary movement from the shaft to said worm, and a sleeve rotatably mounted in a recess formed in said rotor chamber and having a side opening for directing a blast of air against the rotor to rotate said rotor and driving shaft in a predetermined direction according to the position of said sleeve valve.

4. A mounting for a compressed air drill

comprising a support including a threaded track, a carriage carried by said track, a housing carried by said carriage and having a chamber formed therein provided with an air inlet and air outlet, a driving shaft rotatably mounted in said housing and extending through the chamber formed therein, a rotor carried by said shaft within the chamber, means for directing a blast of air from the inlet against the rotor to control the direction of rotation thereof, and means actuated from said driving shaft for engaging the threaded track and imparting movement to said carriage.

5. A drill mounting comprising a support including a threaded track, a carriage slideable upon said track, a housing carried by said carriage and having a chamber formed therein and provided with an air inlet and with an air outlet at the opposite end of the chamber from the inlet, a driving shaft rotatably mounted in the housing and extending through the chamber between the air inlet and the air outlet, a rotor carried by said shaft within said chamber, means actuated from said shaft for engaging said track 70 and imparting movement to said carriage, a sleeve rotatably mounted in the inlet and having a side opening for admitting air to said chamber, the chamber being provided with auxiliary outlet openings, above and below 75 the sleeve whereby a portion of the air passing through the sleeve may be directed out of said chamber, a coupling carried by said sleeve for engaging an air pipe, and means for imparting rotary movement to said 80 sleeve.

6. A compressed air drill mount comprising a support including a track having threads, a carriage including an upper plate resting upon the track and having depending 95 side flanges, lower strips carried by the side flanges and extending to engage the track and retain the carriage in place thereon, means carried by the carriage for engaging a compressed air drill and holding the same 10 in engagement therewith, a housing carried by said carriage, and actuating means in said housing operatively engaging the threads of said track for moving the carriage longitudinally of the track.

In testimony whereof I have hereunto set my hand.

GINES PEREZ GOMEZ.
